United States Patent Office.

HENRY SWINEFORD, OF MIFFLINBURG, PENNSYLVANIA.

Letters Patent No. 99,492, dated February 1, 1870.

IMPROVEMENT IN SCAFFOLDS.

The Schedule referred to in these Letters Patent and making part of the same

To all whom it may concern:

Be it known that I, HENRY SWINEFORD, of Mifflinburg, in the county of Union, and in the State of Pennsylvania, have invented certain new and useful Improvements in Scaffolds; and do hereby declare that the following is a full, clear, and exact description thereof, reference being had to the accompanying drawings, and to the letters of reference marked thereon, making a part of this specification.

The nature of my invention consists in the construction and arrangement of a scaffold capable of being extended, and contracted, and adjusted to suit any unevenness in the ground, all as hereinafter more fully set forth.

In order to enable others skilled in the art to which my invention appertains, to make and use the same, I will now proceed to describe its construction and operation; referring to the annexed drawings, in which—

Figure 1 is a side elevation, and

Figure 2, a front view of my machine;

Figure 3 is a horizontal section of the same; and

Figure 4 shows one of the springs which support the sliding portions of my scaffold.

A A represent two uprights, placed at suitable distances apart on the bed-piece B, and connected at their upper ends, on the rear side, by a cross-bar, C.

The uprights A A are further connected by inclined bars D D, with the ends of the bed-piece B, and are thus firmly braced on the same.

Upon each side of the bed-piece B, about the centre, is hinged a bar, E, and this bar is, by means of a hinged brace, G, at its outer end, connected with a cross-bar, H, which is attached to the two uprights A A in the following manner:

To each end of the cross-bar H is secured a slotted metallic plate or bar, b, secured to the upright by means of a screw, a, passing through said slot.

By raising or lowering the cross-bar H, and fastening it by the screws a a at any desired point, the hinged bar E can be placed at any angle, and consequently support the scaffold on uneven ground exactly the same as on level ground.

Between the standards A A is placed a frame, I, which is raised and lowered, as will be hereinafter set forth.

The outer sides of the frame I are grooved for a

certain distance, and lugs e e, on the inner sides of the uprights A A, fit in said grooves.

In like manner a certain portion of the uprights is grooved, and lugs on the frame fit in said grooves, and in this manner the frame I is prevented from moving sideways, but allowed to move up and down.

Another frame, J, is attached to the front side of the frame I, by means of clamps f f, as shown in fig. 3, said clamps being so formed that the frame J can slide up and down upon the former frame.

At the lower end of the frame J is a platform, K, and at the upper end is a windlass, L.

The windlass L is, by a rope, h, connected with the lower end of the frame I, said rope passing over a pulley, d, on top of the cross-bar C.

Another rope, i, passes from the upper end of the frame J, over a pulley, k, in the top of the frame I, and hangs down in front.

To work the ladders or frames, a pin, m, is put through the frame J, into the frame I. Then the windlass is turned, winding up the rope h, which raises the inside frame I.

When this frame has been raised as high as possible, a spring, n, shown in figs. 2 and 4, holds the frame in this elevated position.

The pin m is then taken out, and the rope i hooked to the former rope, and, by turning the windlass again, the frame J is raised to the top, and a spring, p, catches and holds it, as seen in fig. 1.

To lower, it is only necessary to reverse the above order.

Having thus fully described my invention, what I claim as new, and desire to secure by Letters Patent, is—

1. The combination of the hinged bar E, hinged brace G, cross-bar H, slotted bars b b, and screws a a, all substantially as and for the purposes herein set forth.

2. The combination and arrangement of the bar E, brace G, bar H, slotted bars b, uprights A A, frames I J, platform K, and windlass L, with ropes h i, all constructed and operated substantially as set forth.

In testimony that I claim the foregoing, I have hereunto set my hand, this 8th day of December, 1869.

Witnesses: HENRY SWINEFORD.

SAMUEL HOSENPLUGH,
JAMES BAUM.
